UNITED STATES PATENT OFFICE.

JOHN FREDERICK ZIMMERMAN, OF WAYNESBORO, PENNSYLVANIA.

METALLIC TIE.

1,131,588.

Specification of Letters Patent.

Patented Mar. 9, 1915.

Application filed October 31, 1914. Serial No. 869,845.

To all whom it may concern:

Be it known that I, JOHN F. ZIMMERMAN, a citizen of the United States, residing at Waynesboro, in the county of Franklin and State of Pennsylvania, have invented new and useful Improvements in Metallic Ties, of which the following is a specification.

The present invention relates to improvements in metallic ties for railway rails.

10 In carrying out my invention I propose to construct a metal tie which shall be rolled or molded in a single strip and which shall include rail seats which are elevated from the body of the tie, said rail-seats being provided with ribs or upstanding side members to engage with the longitudinal edges of the base flanges of the rails to prevent the lateral movement of said rails upon the ties, suitable securing elements being provided for 20 retaining the rails upon the seats.

It is a still further object of the invention to provide a metal tie having its body portion corrugated transversely so that the same will be firmly embedded within the 25 roadbed, and also to impart sufficient resiliency to elevate the rail seats formed with the body, so that danger of breakage of the tie will be effectively obviated, and also whereby the ties will be prevented from 30 movement in the roadbed.

With the above and other objects in view, the improvement resides in the construction, combination and arrangement of parts set forth in the following specification and falling within the scope of the appended claims.

In the drawing: Figure 1 is a top plan view illustrating rails supported upon ties constructed in accordance with the present invention, Fig. 2 is a sectional view on the 40 line 2—2 of Fig. 1, and Fig. 3 is a detail perspective view of one of the ties.

The ties 1 are provided, adjacent their ends, with elevated rail seats 2, the said seats being horizontally straight and having 45 their outer edges formed with upturned members or ribs 3 which engage with the opposite longitudinal edges of the base flanges of the rails 4. The ribs 3 are provided with central rectangular depressions or cut-away 50 portions 5 which are centrally provided with openings 6, and passing through the said openings 6 are the shanks 7 of headed members 8. The heads of the members 8 rest in suitable pockets 9 provided therefor in the 55 underface of the tie, and the depressions 5 are adapted to receive rail engaging clips

10, the said shanks passing through suitable openings in the said clips and receive securing nuts 11. The clips are, of course, provided with rail engaging lips 12, the said lips contacting with the upper faces of the base flanges of the rails and having their ends engaging with the webs of said rails.

The seats 2, from the outer edges of their webs are inclined downwardly at opposite angles to the body of the tie, as indicated by the numerals 13 and 14, and the body of the tie, including the central portion 15 and the ends 16 thereof are of a wavy construction, or are corrugated, the convex portions of the waves or corrugations being indicated by the numerals 17 and the intersecting or connecting concaved portions being indicated by the numerals 18, the said concaved and convexed portions extending laterally of the tie. The inclined portions 13 and 14 may also be corrugated, and preferably the same are not only inclined but rounded to the central portion 15 and the ends 16 of the said tie.

By an arrangement as above described, it will be noted that the wavy or corrugated portions of the tie will be readily embedded in the roadbed for the ties, preventing the said ties from moving either laterally or longitudinally. It will be also noted that 55 the natural resiliency of the metal tie and the peculiar construction thereof will permit of the said tie yielding sufficiently when under the weight of the rolling stock passing over the rails to prevent breakage of the tie 90 or injury to the rails.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

1. A tie formed from a strip of metal including elevated rail seats, the ends of which being inclined in opposite directions to the body of the tie, and the said body having transverse corrugations.

2. A tie constructed from a rectangular metal plate including horizontally straight rail seats, the ends of which being inclined in opposite directions to the body of the tie, and the said body being corrugated.

3. A tie constructed from a rectangular metal plate including horizontally straight

rail seats provided with spaced ribs, the said seats being curved in opposite directions to the central portion of the body and to the ends of the tie, and the said body and ends 5 being corrugated transversely.

4. A tie formed from a rolled strip of metal provided with horizontally straight elevated rail seats, the said seats having their longitudinal edges formed with up- 10 standing ribs, the ribs being provided with central depressions, the lower walls of the depressions being provided with openings, and the said openings communicating with the pockets arranged upon the underface of

the tie, the sides of the rail seats being in- 15 clined in opposite directions toward the central portion of the body and to the ends of the tie, the said inclined portions being corrugated and the central portion of the body and ends of the tie being transversely corrugated. 20

In testimony whereof I affix my signature in presence of two witnesses.

JOHN FREDERICK ZIMMERMAN.

Witnesses:

ZELLA BARNITZ,
JOHN A. POTTER.
